T. J. KAUFMAN

LAVATORY FITTING

Filed Aug. 4, 1921

Patented Feb. 12, 1924.

1,483,850

UNITED STATES PATENT OFFICE.

TOBIAS J. KAUFMAN, OF CHICAGO, ILLINOIS, ASSIGNOR TO TECK MANUFACTURING COMPANY, OF CHICAGO, ILLINOIS, A CORPORATION OF ILLINOIS.

LAVATORY FITTING.

Application filed August 4, 1921. Serial No. 489,918.

To all whom it may concern:

Be it known that I, TOBIAS J. KAUFMAN, a citizen of the United States, residing at Chicago, in the county of Cook and State 5 of Illinois, have invented certain new and useful Improvements in Lavatory Fittings, of which the following is a specification.

My invention relates to that class of waste fittings for use in connection with plumbing 10 fixtures in which means is provided for operation of the waste plug at a point other than from the inside of the basin, so that it is not necessary for user to reach into the dirty water to empty the basin.

15 The objects of my invention are to provide a suitable and substantial mechanism which is simple and positive in action and which does not depend upon stuffing boxes or friction to hold the fixture in either an open or 20 closed position. A further object of my invention is to eliminate the ordinary stuffing boxes in the discharge portion of the fitting where leakage often occurs after the fitting has been used for some time.

25 Other objects of the invention will be made apparent in the following specifications, when considered in connection with the drawing forming a part thereof.

In said drawing the single figure is a 30 fragmentary sectional detail, taken transversely of a basin fitted with my improved means for causing vertical reciprocation of the waste plug.

Now referring specifically to the drawing, 35 A is a lavatory provided with the usual overflow passage B. An operating handle C, here shown as in the form of a knob, is secured to a vertically reciprocable rod D. It is to be understood that the invention is 40 not limited to the use of the knob handle C, as any other form of handle may be used, so long as it is adapted for utilization to vertically reciprocate the rod D.

The rod D extends vertically through the 45 top slab of the lavatory A, behind the rear wall of the passage B, a suitable bushing E surrounding the rod and extending through the lavatory slab, being secured in position by a nut F, and washer G.

50 The lower end of the rod D carries a bushing H, provided with a rounded recess adapted to receive a ball K, and an apertured nut J is screwed on to said bushing H, and is provided with a rounded recess around said aperture, complementary to the

recess in the bushing H. The nut J retains the ball K in position, while permitting movement as a universal joint.

A connecting rod L extends through the aperture in the nut J, and is screw-threaded into the ball K. The lower screw-threaded end of said rod L extends through an inferiorly screw-threaded collar M', carried by an arm M, pivotally secured at its lower end at M² to a link N, and to a telescopic member O. A yoke P is made integral with a collar Q, and the rear end of the link N is pivoted at R to the outer end of said yoke.

An elongated sleeve S telescopically surrounds the member O, and is provided with 70 a rounded inner end S'. A coiled spring T is held within the member O, and is compressible by each reciprocation of said member towards the closed end of the sleeve S.

A diaphragm U is positioned in a peripheral groove around the sleeve S, and is securely held in position by the collar Q, which clamps it against a casting V, formed integral with a coupling V', screw-threaded on to a sleeve V², which extends into the 80 waste aperture of the basin, and secured in position by bushings, as shown. The waste plug X is adapted to a seat X', and is provided with elongated, laterally extending guiding flanges X², which extend downwardly into the coupling V', and terminate in a ring X³. An outlet waste pipe Y is secured to the lower portion of the casting V.

A rod W is screw-threaded through the 90 end S' of the sleeve S, the outer end of said rod passing through the ring X³.

A collar Y', provided with a flange Y², is screw-threaded on to the casting V and the collar Q, and holds the latter and the yoke 95 P in position.

It is to be noted that the inner peripheral edge of the collar Q is beveled, and that the casting V, where apertured to permit passage of the rounded end S', is oppositely beveled around said aperture. This construction not only permits flexure of the diaphragm U, but the bevel in the casting V provides a bearing for the rounded end S' of the sleeve S.

The device is here shown with the plug X in its closed position, the spring T tending to press the rod L upwardly, and, therefore tending to hold the plug in closed position. If it is now desired to raise the 110

2
plug X, the handle C is depressed, which causes the arm M to impart downward pressure at M², to the outer end of the member O. When such pressure overcomes the pressure of the spring T, the member O will slide further into the sleeve S, straightening the toggle joint and further compressing the spring T. Such straightening movement of the toggle, formed by the link N, 10 the member O, and the sleeve S, causes the rod W to rise upwardly and raise the plug X, as will be obvious. In the raised position of the plug the spring T will be under great compression, which is exerted against 15 the pivotal point R, tending to hold the plug in its raised position. When it is desired to again lower the plug X, a slight upward pull upon the handle C will be sufficient to move the toggle out of its straight 20 line, and the spring T will obviously cause the plug X to snap down into position.

Because of the screw-threaded connection between the lower end of the rod L and the collar M', it is obvious that the fitting is 25 adapted for use with lavatories of varying dimensions between the supporting slab and the bottom of the bowl. By rotation of the rod L the collar M' may be moved vertically, thereby permitting installation of the 30 fitting into any lavatory, as will be understood.

Modifications of the structure herein shown will be suggested to those skilled in the art, but my invention covers all embodiments falling within the scope of the 35 appended claims.

I claim:

1. A fitting provided with a waste outlet, a plug adapted for movement to open 40 and close said outlet, a toggle mounted adjacent the fitting casing and carrying a rod extending through the casing and operatively connected to said plug, and means for pivotally moving the toggle and thereby reciprocating said rod, whereby to move 45 said plug to its open or closed position, substantially as described.

2. A fitting provided with a waste outlet, a plug adapted for movement to open 50 and close said outlet, a toggle mounted adjacent the fitting casing and carrying a rod extending through the casing and operatively connected to said plug, means for pivotally moving the toggle and thereby reciprocating said rod, whereby to move 55 said plug to its open or closed position, and a spring carried by said toggle and adapted to be expanded or compressed under the pivotal movements of the latter, whereby to accelerate the movement of the plug 60 towards and away from its closing position, substantially as described.

3. A fitting provided with a waste outlet, a plug adapted for movement to open 65 and close said outlet, a toggle mounted ad-

jacent the casing and having one of its arms pivotally mounted in a wall of the latter, a rod carried by said arm and extending through said wall and operatively connected to said plug, whereby pivotal movement of said arm may move said plug towards or away from said outlet, and a member adapted for actuation to effect pivotal movement of the arms of said toggle, substantially as described. 70 75

4. A fitting provided with a waste outlet, a plug adapted for movement to open and close said outlet, a toggle mounted adjacent the casing and having one of its arms pivotally mounted in a wall of the latter, a rod carried by said arm and extending through said wall and operatively connected to said plug, whereby pivotal movement of said arm may move said plug towards or away from said outlet, a member 80 adapted for movement to open and close said toggle, and a spring carried by said toggle and adapted to be expanded or compressed under the pivotal movements of the latter, whereby to accelerate the movement 85 of the plug towards or away from its closing position, substantially as described. 90

5. A fitting provided with a waste outlet, a plug adapted for movement to open and close said outlet, a toggle mounted adjacent the fitting and carrying an arm extending through an aperture in the casing of the fitting, a flexible hinge carried by said arm and sealing said aperture around said arm, a rod connected to said plug within the casing and secured at one end to said arm, and a member adapted to pivotally operate said toggle to cause said plug to move towards its opening and closing positions, substantially as described. 95 100 105

6. A fitting provided with a waste outlet, a plug adapted for movement to open and close said outlet, a toggle mounted adjacent the fitting and carrying an arm extending through an aperture in the casing 110 of the fitting, a flexible hinge carried by said arm and sealing said aperture around said arm, a rod connected to said plug within the casing and secured at one end to said arm, a member adapted to pivotally operate said toggle to cause said plug to move towards its opening and closing positions, and a spring carried by said toggle and adapted to be expanded or compressed under the pivotal movements of the latter, 115 whereby to accelerate the movement of the plug towards or away from its closing position, substantially as described. 120

In testimony whereof I affix my signature in presence of two witnesses.

TOBIAS J. KAUFMAN.
